UNITED STATES PATENT OFFICE.

HENRY J. ENNIS, OF WASHINGTON, DISTRICT OF COLUMBIA, ASSIGNOR TO
GEORGE McGOVERN, OF RICHMOND, VIRGINIA.

LIFE-PRESERVER.

SPECIFICATION forming part of Letters Patent No. 664,395, dated December 25, 1900.

Application filed April 19, 1900. Serial No. 13,527. (No model.)

To all whom it may concern.

Be it known that I, HENRY J. ENNIS, a citizen of the United States, residing at Washington, in the District of Columbia, have invented 5 certain new and useful Improvements in Life-Preservers; and I do declare the following to be a full, clear, and exact description of the invention, such as will enable others skilled in the art to which it appertains to make and 10 use the same.

My invention relates to certain novel improvements in life-preservers, and more particularly to that class wherein the preserver is combined with a bathing-suit or other article of wearing-apparel; and the object of the invention is, primarily, to provide a pneumatic life-preserver with means for automatic inflation, and, secondly, to provide an article of wearing-apparel with a pneumatic life-preserver capable of automatic inflation.

To these ends the invention consists in a pneumatic life-preserver adapted to be automatically inflated.

The invention further consists in a pneumatic life-preserver, in combination with a cartridge or other suitable holder containing a charge of compressed air or gas arranged to inflate the preserver.

It also consists of a pneumatic life-preserver, in combination with a cartridge or holder containing a charge of calcic carbid, to which water may be added to produce acetylene gas for the purpose of automatically inflating the preserver at will.

My invention further consists in the construction, combination, and arrangement of the several elements of the device, as will be hereinafter more fully described, and particularly pointed out in the claims.

In the accompanying drawings the same reference characters indicate the same parts of the invention.

Figure 1 is a perspective view, partly in section, of my improved life-preserver as it appears in use and with the preserver shown deflated. Fig. 2 is a similar view with the preserver represented as being inflated. Fig. 3 is a perspective view of the preserver detached from the bathing-suit. Fig. 4 is a 50 similar view of the preserver constructed in

the form of an ordinary waistcoat or vest. Fig. 5 is a detail view of the air or gas cartridge. Fig. 6 is a similar view of the carbid-cartridge. Fig. 7 shows another form of the carbid-cartridge.

55

A designates an ordinary bathing-suit, and secured thereto by stitching, as at a, is an inflatable life-preserver B. This preserver B may be of any suitable size, shape, and material to correspond to the use to which it is 60 to be put, and it is provided with a neck or tube b, in which is secured an internally-threaded sleeve or collar b', or, if desired, the neck or tube may be dispensed with and the sleeve or collar secured directly in the body 65 of the fabric comprising the life-preserver.

C designates the cartridge or holder, and it is provided with an externally-threaded stem c, so that it may be detachably connected to the collar b'. This cartridge is provided with 70 a valve c' to retain the charge of compressed air or gas in the cartridge, and when the latter is attached to the life-preserver the valve may be withdrawn from its seat to allow the confined air or gas to escape into the preserver and inflate it. In the form of cartridge shown in Fig. 6 the cartridge is divided into two compartments separated by the valve c', and one of these compartments is adapted to 75 contain the carbid and the other a small 80 amount of water, which when brought into contact with the carbid causes acetylene to form, which escapes into the preserver and automatically inflates it. In Fig. 7 I have substituted the rubber check-valve d for the 85 screw-valve c', and the cartridge contains the carbid alone, so that when the preserver and attached cartridge are submerged, as in the instance of a person falling or jumping overboard, the pressure of the water would force 90 the check-valve inward, and the water coming in contact with the carbid generates the acetylene, which inflates the preserver, the pressure of the gas forcing the valve outward against its seat and confining the gas.

95 Of course it will be readily understood that the cartridge-inflation principle can be applied to pillows, mattresses, life-rafts, divers' suits, and a variety of other marine uses.

In the accompanying drawings I have shown 100

my invention in the best form now known to me; but obvious changes may be made in the details without departing from the spirit of my invention as set forth in the claims.

5 Having thus fully described my invention, what I claim as new and useful, and desire to secure by Letters Patent of the United States, is—

1. As a new article of manufacture, a life-preserver comprising a collapsible impermeable belt provided with a single opening, and a cartridge charged with liquefied gas and detachably connected with said belt in said opening, said cartridge being provided with 15 a self-closing valve having a pressure-button, for the purpose set forth.

2. The inflating-cartridge for use in connection with life-preservers and analogous buoyant bodies having a single opening, said 20 cartridge having a valve adapted to be closed by the pressure of the liquefied inflating medium, and having a screw-threaded mouth,

and a pressure-button for opening said valve, for the purpose set forth.

3. The combination with an inflatable vessel of an integral detachable cartridge adapted to have its body portion wholly inserted within said vessel, and having one end opening into the vessel and the other opening into the atmosphere, for the purpose set forth. 30

4. The combination with an inflatable vessel, of an integral detachable cartridge adapted to have its body portion wholly inserted within said vessel, and means for establishing communication between said vessel and 35 cartridge, for the purpose set forth.

In testimony whereof I have hereunto set my hand in presence of two subscribing witnesses.

HENRY J. ENNIS.
